UNITED STATES PATENT OFFICE.

ROBERT O. WOOD, OF ELIZABETH, NEW JERSEY, ASSIGNOR OF ONE-HALF TO PITSER MILLER, OF ELIZABETH, NEW JERSEY.

ORNAMENTAL TUBULAR FORM.

Application filed March 23, 1925. Serial No. 17,597.

To all whom it may concern:

Be it known that I, ROBERT O. Wood, a citizen of the United States, and resident of Elizabeth, county of Union, State of New Jersey, have invented an Improvement in Ornamental Tubular Forms, of which the following description, in connection with the accompanying drawings, is a specification, like characters on the drawings representing like parts in each of the several views.

This invention relates to articles for decorative and ornamental purposes in household use, and more particularly to a decorative device embodying a container tube of glass or like transparent material that is filled with tightly compressed yarn or floss of colored silk, mercerized cotton or the like. The device thus constituted is adapted for embodiment in articles such as decorative candles, towel bars, electric-light fixture candles or decorative covers, and other embodiments where a tubular ornamental form might advantageously be utilized. I have discovered that the sheen or luster exhibited by yarn or floss contained within a glass tube is greatly enhanced by the flattening and pressing closely of the yarn against the glass, and in my prior application S. N. 694,528, filed February 23, 1924 I have shown and claimed this invention in its broader aspects and in one embodiment thereof. The present invention is in the nature of an improvement and modification of the embodiment of the invention as shown in my prior application and has as its principal object a greater economy of manufacture of decorative tubes of this character, particularly in the larger sizes such as are employed for towel bars and the like, though the invention is also applicable to decorative candles and the like if desired. In accordance with the present invention I economize in the use of the decorative yarn or floss by laying the same on a gummed paper or like backing sheet, and then after fitting said sheet in the tubular form so that the yarn lies evenly against, and covers the interior wall of the tube, the interior space of the tube is filled with tightly packed stuffing such as cheap cotton waste or the like.

The foregoing and other objects and advantages of the invention will more fully appear from the following detailed descrip-

tion taken in connection with the accompanying drawings, and the distinctive features of novelty will be pointed out in the appended claims.

Referring to the drawings:

Fig. 1 is an elevation of a gummed paper sheet showing the same partly covered with decorative yarn or floss in accordance with my invention. 60

Fig. 2 is a transverse section thereof 65 on line 2—2 of Fig. 1.

Fig. 3 is an elevation of a decorative candle embodying the invention.

Fig. 4 is an elevation on a relatively smaller scale showing a towel bar embodying the invention. 70

Fig. 5 is a fragmentary longitudinal section showing one end of a decorative tube produced in accordance with my invention; and 75

Fig. 6 is a transverse section on line 6—6 of Fig. 4.

10 indicates a sheet of paper having a suitable adhesive gum applied to one side thereof. On this gummed surface yarn or 80 floss 11 is laid either in a close, parallel, longitudinal order, or other order or arrangement that may be preferred, so as to cover the entire surface of this gummed side of the paper,—the yarn being thus held in a definite position on the paper sheet. The gummed paper is then inserted and fitted in a glass tube which may be either a decorative candle form as indicated at 12 in Fig. 3, or it may be a glass towel bar 85 as indicated at 13 in Fig. 4. The yarn or floss thus disposed against the inside surface of the glass tube is tightly compressed against such surface by any proper or suitable means, for example, by stuffing the tube with cheap cotton waste or the like,—thus causing the yarn or floss to exhibit a greatly enhanced luster and sheen by reason of such compression and flattening of the yarn against the glass. The ends of the tube in 100 the towel bar type of Fig. 4 and the inner end of the candle form of Fig. 3 may be closed by a suitable plug 14, while in the case of the candle, the reduced end 12^a thereof may have strands of the yarn projecting therefrom as indicated at 15 to simulate the candle flame. 105

I am aware that the invention may be embodied in other specific forms without departing from the spirit or essential at- 110

tributes thereof, and I therefore desire the present embodiment to be considered in all respects as illustrative and not restrictive, reference being had to the appended claims 5 rather than to the foregoing description to indicate the scope of the invention.

Having described my invention, what I claim as new and desire to secure by Letters Patent is:

- 10 1. An ornamental tubular form, comprising a transparent tube, a flexible sheet having yarn or floss adhesively secured thereto and fitted in said tube to expose such yarn against the inner wall of the tube, and 15 means for pressing closely and flattening such yarn against the walls of the tube.
2. An ornamental tubular form, comprising a transparent tube, a flexible sheet having ornamental yarn or floss adhesively se-

cured to one side thereof, with said sheet 20 fitted in said tube so that the yarn is laid against the walls of the tube, and means for filling out the interior of the tube so as to exert substantial pressure upon said yarn to press it tightly and flatten it against the 25 walls of the tube.

3. An ornamental tubular form, comprising a glass tube, a paper sheet having yarn adhesively secured to one side thereof in a pre-determined order, with said sheet 30 fitted in such tube so that the yarn is exposed against the walls thereof, and means for stuffing the interior of the tube to press such yarn tightly and closely against the inner surface of the tube. 35

In testimony whereof I have signed my name to this specification.

ROBERT O. WOOD.
